The figure is a plan view of a folded napkin incorporating the design of the invention.

The essential feature of the invention resides in the particular configuration in which multiple clusters of four fleurs-de-lis are aesthetically arranged about intersecting lines located in fields disposed at the corners of a napkin, which fields, themselves, are separated from the contrasting body of the napkin by serpentine chains matching the border circumscribing the napkin.

This is a division of application Serial No. D. 78,131, filed January 8, 1964.

I claim:

The ornamental design for a napkin or the like, substantially as shown and described.
